UNITED STATES PATENT OFFICE.

JOSEPH P. BAUMGARTNER, OF PHILADELPHIA, PENNSYLVANIA.

HOOK AND EYE.

No. 900,469.

Specification of Letters Patent.

Patented Oct. 6, 1908.

Application filed February 27, 1906. Serial No. 303,175.

To all whom it may concern:

Be it known that I, JOSEPH P. BAUMGARTNER, a citizen of the United States, residing in the city and county of Philadelphia, State 5 of Pennsylvania, have invented a new and useful Hook and Eye, of which the following is a specification.

My invention relates to new and useful 10 hooks and eyes and consists in providing means for attaching the hook and eye to a garment or desired material.

It further consists in providing a locking 15 point where the hook or eye engage with the garment or material whereby the same will be held in position.

It further consists in providing means for engagement with the garment or material on each side of the locking point.

It further consists of other novel details of 20 construction all as will be hereafter fully set forth.

Figures 1, 2, 3 and 4 represent different forms of eyes showing the same means for fastening the same to the garment. Fig. 5 25 represents a hook which may be employed in conjunction with the eyes. Fig. 6 represents in elevation, a piece of material with the hooks and eyes in position from the front. Fig. 7 represents a perspective view showing 30 the inner portion of the hook in position on the garment. Fig. 8 represents an enlarged view showing a hook and eye in position with the material partly broken away.

Similar numerals of reference indicate corresponding parts in the figures.

Referring to the drawings:—1 designates an eye embodying my invention preferably formed of wire, the same consisting of the loop or eye proper 2, the sides of which are 40 drawn towards each other and substantially abut as at 3, from which point the locking eyes or locking points 4 and 5 are formed by curving the wire around outwardly and forwardly towards the sides of the loop 2 forming the passageways 7^x therebetween and then bending the same rearwardly as at 7 forming the arms 6, the said portions 7, of which, form abutting edges, as will be hereinafter described. Each of the arms 6 carries the pins 8 and 9 which in the present case are shown flattened, as will be seen and which are substantially straight, one of said pins 8 being shorter than the other.

The constructions above described is clearly 55 shown in Fig. 1 and in Fig. 2 the same con-

struction is followed as far as locking points or eyes 4 and 5 are concerned and also the abutting edges 7 and pins 8 and 9, the difference being, that in Fig. 2, the loop proper 10 is of triangular shape but forms 60 the passageways 7^x as before.

In Fig. 3 the construction differs in that the loop proper 11 is triangular and has the rearwardly extending members 12 and 13 which are substantially parallel and which 65 are curved outwardly and then forwardly forming the locking points 4 and 5 and the passageways 7^x as before, the remaining portions of the eye being the same.

In the construction shown in Fig. 4 I have 70 made a different for of loop proper 14 but with the other features the same as heretofore described.

In Fig. 5 I show the same features employed in connection with the hook. In this 75 construction it will be seen that the same pins 8 and 9 are used for the initial piercing of the material, the side members 6 being a trifle larger than heretofore shown but the locking points or eyes 4 and 5 being formed 80 as already described.

The method of fastening the eye or the hook to the material at the place at which it is desired is as follows, the material is first pierced by the longest of the two pointed 85 arms or pins, in this instance 9, until the arm is nearly inserted to its full length into the material or until the distance between the end of pin 8 and the opening in the material caused by the insertion of arm 9, substantially corresponds with the space between the two locking points 4 and 5, where the material is ultimately to lie. The shorter of the two arms 8 is forced into the material and the material is then drawn forward over the arms or members 6 and over the top of the rounded part or abutment 7 and then between this portion and the arms of the loop proper that is the passageway 7^x until it is situated in the locking eye or point 100 4, that is on the side which has the shortest point 8. The material is then relaxed from strain and the pin 8, the arm 6 and the portion 7 is on the opposite side of the material from the eye 2. The material is then forced over the other arm 6 and other rounded or abutting point 7 into the locking eye or point 5 so that the loop 2 will, from the front, be 105 in the position as seen in Fig. 6, while the other portion of the eye will be upon the op- 110

posite side of the material, as seen in Fig. 7, the whole being firmly held in position. The eyes or locking points engage the material and the material will be grasped between the inner edges or sides of each rounded portion 7 and the contiguous portion of the loop 2 where the inner curve of part 7 and the sides of the loop come almost in contact.

10 The above description will also apply to the means or manner of inserting the hook in the material which will likewise also be held firmly in position. As seen in Fig. 6 the eye is attached to the material close to the edge thereof in order that the loop proper 2 projects sufficiently beyond the material for ease of engagement with the hook and when the parts are in position the rounded portions or abutting edges 7 will be situated adjacent to and abutting against the hem or turned up edge of the material and assist in taking some of the strain from the locking eye or points 4 and 5. In addition by stitching along the material adjacent 25 the pins 8 and 9, as at 17, the parts will be still more firmly held in position.

In Figs. 6 and 8 I have shown clearly the stitching 17 in the material adjacent the pins 8 and 9, it being seen with respect to the eye 30 that as before stated, the abutting points 7 are so situated as to contact with the bend in

the material made to form the hem and when the stitching 17 is made the eye is substantially in a pocket as will be seen.

With respect to the hook it will be noted that the same is situated a sufficient distance from the edge of the material to form a lap when the two sides of the material are brought together and the hook and eye are joined. In this instance I stitch the material as at 18 adjacent the abutting points 7, the effect of which being that the hook is substantially in a pocket formed by the stitching 17 and 18, the effect of which is evident.

Having thus described my invention, what I claim as new and desire to secure by Letters Patent, is:—

1. In a device of the character described, a member of a hook and eye fastener having locking eyes and passage ways to the locking eyes in which the material is adapted to be grasped, and overlapping attaching pins.

2. In a device of the character described, a member of a hook and eye fastener, locking eyes therefor, and pins extending in opposite directions and overlapping for piercing the material.

JOSEPH P. BAUMGARTNER.
